CLAIM

The ornamental design for a tailstock alignment bar, as shown and described.

DESCRIPTION

FIG. 1 is a top left perspective view of a tailstock alignment bar showing my new design;

FIG. 2 is a close-up split view of FIG. 1, the broken lines form no part of the new design;

FIG. 3 is a top elevational view thereof;

FIG. 4 is a close-up split view of FIG. 3, the broken lines form no part of the new design;

FIG. 5 is a right end elevational view thereof; and,

FIG. 6 is a left end elevational view thereof.
